UNITED STATES PATENT OFFICE.

JOHN JANICKI, OF OAK PARK, ILLINOIS, ASSIGNOR TO WESTERN ELECTRIC COMPANY, INCORPORATED, OF NEW YORK, N. Y., A CORPORATION OF NEW YORK.

METHOD OF AND APPARATUS FOR SERVING MATERIAL UPON A CORE.

Application filed September 4, 1925. Serial No. 54,398.

To all whom it may concern:

Be it known that I, JOHN JANICKI, a citizen of the United States, residing at Oak Park, in the county of Cook and State of Illinois, have invented certain new and useful Improvements in Methods of and Apparatus for Serving Material upon a Core, of which the following is a full, clear, concise, and exact description.

10 This invention relates to methods of and apparatus for serving material upon a core, and more particularly to a method of and apparatus for simultaneously serving a plurality of strands upon a core.

15 In insulating wire for electrical purposes it is frequently the practice to serve the wire core with a plurality of strands of silk, cotton, or other insulating materials, which to expedite the serving operation have been assembled into a band or a composite or multi-end strand and wound into a cop. The individual strands, which may be differently colored to comprise an identifying covering for the wire, are arranged to form a single

20 layer as they are served upon the core. It has been proposed, in one instance, that these strands be separated or fanned along the axis of the core and served thereon from a common line disposed radially with respect to the core. However, it has been found that only a limited number of strands may be satisfactorily and uniformly served in a simultaneous manner by such a method.

25 The objects of the invention are to provide an improved method of and an improved apparatus for rapidly and uniformly serving an unlimited number of strands upon a core.

30 In order to attain this object in accordance with one embodiment of this invention, a plurality of strands are withdrawn from a cop or other supply to a common point, or a multi-end strand is drawn thereto, which point is located at a distance from the periphery of a core to be served. The strands or the ends composing the multi-end strand, are fanned from the common point to a plurality of non-uniformly spaced points so distributed as to maintain them separated. They are individually guided therefrom to a corresponding number of points uniformly spaced around the core and then served to the core at substantially equal angles to form a single layer thereon.

35 In one embodiment of the invention in an

apparatus by means of which the method may be practiced, a serving mechanism of a usual type wherein a core is drawn vertically through the axis of a horizontally rotating cop holder and serving head from which the strands are served, is provided with a distributing head or plate secured to the serving head. The distributing plate is provided with a plurality of slotted apertures, the bottom or inlet ends of which are non-uniformly spaced to maintain the strands fed from a common point, separated from each other and from the serving head, while the upper or outlet ends of the apertures are uniformly spaced around the core. The rotation of the head serves the strands from the outlet ends of the apertures at substantially equal angles to the core.

40 Other objects and advantages of this invention will more fully appear from the accompanying detailed description taken in connection with the accompanying drawings which illustrate one embodiment thereof, in which—

45 Fig. 1 is a vertical sectional view partly in elevation through a serving head embodying the features of this invention;

50 Fig. 2 is a plan view thereof;

55 Fig. 3 is an enlarged side view of the multi-strand guiding device of this invention, and

60 Fig. 4 is a plan view thereof.

65 Referring to the drawings wherein like reference numerals designate like parts throughout the several views, 10 indicates a horizontal plate carrying a rim 11 provided with suitable openings 12 and 13 for the threading of the serving material from a cop or bobbin 14. The plate 10 is rigidly secured to a hollow driving spindle 15 by a driving fit or otherwise, the spindle projecting a suitable distance above it and forming a bearing about which a sleeve member 16 provided at its lower end with an annular flange 17 may revolve. The plate 10, rim 11, spindle 15 and sleeve 16 comprise what is generally known in the art of strand serving or twisting as a serving head. The cop 14 is made up of multi-end strand material in the form of a band or ribbon 18 which may be of cotton and in the present instance consists of seven ends or separate strands 19, arranged side by side, the ribbon being wound in crossed helices on a paper tube or core 20. The tube 20 is secured

in position on the sleeve 16 by pressing the tube over a plurality of fins 21 provided upon the sleeve member 16.

Interposed between the flange 17 and the plate 10 is a compression spring 22 which serves to provide a suitable friction between the top surface of the sleeve 16 indicated by the numeral 23 and an adjustable collar 24 threaded upon the upper end of the spindle 15 to prevent the free rotation of the cap and sleeve upon the spindle 15 and thereby provide a desired tension upon the strands 19 during the operation of the serving mechanism.

The extreme threaded upper end of the spindle 15 extends above the top of the rim 11 and is tapered as indicated at 27 and provided with a plurality of slots, one of which is shown at 28, extending downwardly from the end thereof. Adapted to be mounted upon the hollow spindle is a unitary multi-strand guiding device 29, a sleeve-like portion 30 at the lower end thereof being being inserted in the bore of the hollow spindle and clamped thereto by turning a threaded collar 31 downwardly upon the tapered end of the spindle 15. The upper end of the device 29 comprises a circular shaped head or plate 32 provided at its underside with a cone-like face 33 extending from the peripheral edge thereof to the periphery of the sleeve-like portion 30. The upper face of the head 32 is also provided with a cone-like face 34 which extends from a point inside the peripheral edge of the head 32 to the wall of the bore formed in the device 29. The purpose of the cone-like faces 33 and 34 will be made clear as the description progresses. The head 32 is provided in the present embodiment of this invention with seven angularly disposed apertures 37, one for each of the strands 19, which apertures at their outlet ends upon the upper surface of the head 32, are equally disposed, radially and circumferentially with respect to a core 38 being served which serves to direct each strand to a certain predetermined point upon the periphery of the core 38. The apertures 37 are formed at such an angle to the axis of the device and to each other that the inlet ends of the apertures are not equally disposed radially and circumferentially. The angle of each aperture is such that each strand 19 will be guided in passing from the opening 12 in the rim 11 to its respective aperture 37 and upwardly therethrough and to the core 38 being served without engaging any other strand during its travel. Also the strands 60 are guided so that they will not contact with the periphery of the sleeve-like portion 30 and due to the cone-like faces 33 and 34, the guiding surface of the apertures is reduced and consequently friction upon the strands is reduced to a minimum. To facilitate

threading the strands 19 through the device 29 the wall of each aperture 37 is slotted as indicated at 40, the slot extending to the periphery of the head 32 with the peripheral face of the head 32 at one side of each of the slots cut back toward the axis of the device as indicated by the numeral 41. It will be readily apparent that an operative may position each of the strands 19 within an aperture 37 in threading the serving mechanism by merely pressing the strand against the periphery of the head 32 between the slots 40 and slide it toward the cut back portion 41 which will cause it to ride into the slot 40 and therealong into the aperture 37.

It will be observed that the diameter of the device 29 is such that a cop 14 of serving material may be mounted on the serving mechanism without removing the device, the diameter being such that the tube 20 carrying the cop 14 may pass freely thereover.

Referring to Figs. 1, 3 and 4 it will be noted that the strands 19 in passing from the opening 13 in the rim 11 to the core 38 do not engage each other or any portion of the guiding device 29 except the walls of the apertures 37 and their engagement therewith is reduced to a minimum due to the cone-like face 33 at the underside of the guide 29 which serves to reduce the length of the apertures and consequently friction upon the strands. After the strands 19 leave the apertures 37 there occurs a point contact of the strands with the upper peripheral edge of the cone-like face 34 which with the uniform radial and circumferential spacing of the outlet ends of the apertures 37 about the core 38 serves to support and cause the strands to approach the periphery of the core at uniform angles and laid thereon parallel to each other.

The operation of the serving mechanism hereinbefore described is as follows:

The core 38 being served, it will be understood, is drawn through the hollow driving spindle 15 and guiding device 29 by any suitable drawing off mechanism which will insure an even steady movement bearing a substantially fixed relation to the speed of rotation of the driving spindle and the diameter of the strand being served to the core. Drawing off mechanisms of this type being well understood in the art, no attempt has been made to show the same. Upon mounting the cop 14 upon the sleeve 16 in the manner hereinbefore described the end of the multi-end cotton strand 18 is threaded through the openings 12 and 13 in the rim 11 as clearly shown in Fig. 1. Upon leaving the opening 13 it will be readily apparent that the ends 19 of the strand 18 will be separately guided to the core 38 by their passage through the apertures 37 of the device 29 and as hereinbefore explained

due to the uniform radial and circumferential spacing of the outlet ends of the apertures 37 about the core 38 they will be served with a minimum amount of friction and laid 5 parallel thereon with a uniform twist or lay.

A strand guiding device embodying the features of this invention provides for accurate control of the spacing between the strands as they are served to the core there- 10 by preventing open spaces therebetween and piling up of one strand upon another.

What is claimed is:

1. A method of serving a core, which consists in guiding a plurality of strands to a 15 common point, fanning the strands therefrom to a plurality of points distributed around the core and simultaneously serving the strands from said plurality of points to the core and wrapping them therearound.

2. A method of serving a core, which consists in guiding a plurality of strands to a common point, fanning the strands therefrom to a plurality of non-uniformly spaced points so arranged as to maintain the 20 strands separated throughout from the common point, guiding the strands to a plurality of equally spaced points distributed around a core to be served, and serving the strands upon the core therefrom to form a 25 single layer thereon.

3. A method of serving a core, which consists in guiding a plurality of strands to a common point, fanning the strands therefrom to a plurality of points distributed 35 around the core and causing a combined relative rotation between the points and the core and a relative movement therebetween along the axis of the core to serve the strands from the points in a single layer 40 upon the core.

4. In a serving apparatus, means for guiding a plurality of strands from a common supply thereof past a predetermined point, and means removed from the point for separating the strands and serving them to a core from a plurality of points distributed therearound and wrapping them around the core.

5. In a serving apparatus, means for 50 guiding a plurality of strands from a common supply thereof past a predetermined point, and means for fanning the strands therefrom, directing them to a plurality of points distributed around a core, serving them therefrom to the core and wrapping them therearound.

6. In a serving apparatus, means for 55 guiding a plurality of strands from a common supply thereof past a predetermined point, and means for fanning the strands therefrom to a plurality of points distributed around the core equally spaced from each other and from the core, serving the strands therefrom to the core and wrapping them therearound.

7. In a serving apparatus, means for guiding a plurality of strands from a common supply thereof past a predetermined point, and a member rotatable around a core and having a plurality of apertures therein to 70 fan the individual strands from the point and maintain them separated therefrom, the walls of said apertures being disposed at angles so that their outlet ends are uniformly spaced around the core to serve the 75 strands upon the core at substantially the same angle.

8. In a serving apparatus, a serving head for supporting a supply of multi-end strand material, means designed to guide a strand from the supply past a predetermined point and a member secured to the head and rotatable therewith and surrounding a core to be served, said member having a plurality 80 of apertures therein for individually receiving the ends of the strand, maintaining them separated from said predetermined point, and guiding them to the core during the serving operation from points distributed 85 therearound.

9. In a serving apparatus, a serving head for supporting a supply of multi-end strand material and having apertures therein for surrounding a core and for receiving a multi-end strand withdrawn from the supply and a distributor secured to the serving head and having a plurality of apertures therein for fanning the ends of the strand from the aperture in the serving head 90 and guiding them individually to the core at substantially equal angles thereto during the serving operation, the walls of said apertures being angularly disposed to maintain the ends separated throughout from the fanning point to the distributor.

10. In a serving machine, a serving head mounting a cop or bobbin of multi-end strand material, a rotatable strand guiding member carried by said head concentrically of a longitudinally movable core to be served, said member provided with a plurality of strand guiding apertures for the different ends of the material being served, the apertures being equally spaced radially and circumferentially of the core.

11. In a serving machine, a serving head mounting a cop or bobbin of multi-end strand material disposed concentrically of a longitudinally movable core to be served, a rotatable strand guiding member carried by said head concentrically of the core and cop and having a plurality of strand guiding apertures for the different ends of the material being served, the apertures being angularly disposed with their inlet ends spaced non-uniformly and their outlet ends 110 equally spaced radially and circumferentially of the core.

12. In a serving machine, a serving head 115 mounting a cop or bobbin of multi-end

strand material, a rotatable strand guiding member carried by said head concentrically of a longitudinally movable core to be served, said member provided with a plurality of strand guiding apertures for the different ends of the material being served, the apertures being equally spaced radially and circumferentially of the core and slotted to the periphery of said member to admit the ends of material to the apertures. 10

In witness whereof, I hereunto subscribe my name this 26 day of Aug. A. D., 1925.

JOHN JANICKI.
